UNITED STATES PATENT OFFICE

MATTHEW SMOLKO, OF CHICAGO, ILLINOIS

IRON STAND

Application filed May 2, 1932. Serial No. 608,772.

My invention relates to the art of laundry, and it particularly has for its object to provide an iron stand and means to clamp it to an ironing board or table, the construction being such that on making the last stroke of the iron at the conclusion of the ironing operation the stroke may be extended to carry the iron over to and up onto the stand, automatically as it were, without lifting the iron.

Further, the invention has for its object to provide a stand whose iron holding plate is well heat insulated so that the iron may remain on the stand for hours if desired without burning the ironing board pad.

Again, it is an object to provide an iron stand which can be used on either stationary or fold-into-wall-cupboard ironing boards, since it does not have to be removed when the operator is through ironing.

Other objects will in part be obvious and in part be pointed out hereinafter.

To the attainment of the aforesaid objects and ends, the invention still further resides in the novel details of construction, combination and arrangement of parts, all of which will be first fully described in the following detailed description, then be particularly pointed out in the appended claims, reference being had to the accompanying drawings, in which:—

Figure 1 is a perspective view of a portion of an ironing board or table with my invention applied.

Figure 2 is an enlarged end elevation of the invention.

Figure 3 is a side elevation of the invention on a somewhat smaller scale than Figure 2.

Figure 4 is a cross section of the invention on the same scale as Figure 3 but taken on the line 4—4 of Figure 2.

Figure 5 is a detail section on the line 5—5 of Figure 2.

Figure 6 is a plan view of the bottom plate on a reduced scale.

Figure 7 is a plan view of the top plate on the same scale as Figure 6.

In the drawings in which like numerals of reference designate like parts in all the fig-

ures, 1 represents the ironing table or board which may be of any usual construction and which is usually covered by a table pad 2, while 3 designates the electric iron. (Other irons may be used as well as electric ones.)

The structure which comprises my invention consists of an iron receiving plate 4 having flanges 5 on three sides and a lip 6 along one longitudinal edge, the lip being inclined downwardly at an angle of approximately twenty degrees. The plate 4 is provided with countersunk screw holes 7 for a purpose presently understood.

A bottom plate 8 is provided having an upstanding offset 9 and a downwardly inclined extension 10 at the side adjacent the lip 6, the inclination of the extension 10 being approximately seventeen degrees. The bottom plate 8 is provided with a series of holes 12 corresponding in number to the holes 7 and provided for the purpose of receiving the reduced shanks 16 of the insulating bushings (fibre) 15. These bushings 15 have their reduced shanks passed through the holes 14 of the bottom plate 8 and the top plate 4 rests thereon, the same being secured together by screws 19.

The lower edge of the inclined extension 10 is beveled as at 11.

One or more intermediate plates 13 are provided (one being shown for purposes of illustration) and they have holes for the passage of the shanks 16 of the bushings 15, the intermediate plates being spaced from the upper and lower plates by spacer insulation washers 18. The shanks 16 of the bushings 15 are bored and tapped as at 17 for the screws 19.

The lower plate 8 also is provided with a suitable number of suitably spaced screw holes 20 for securing the clamp thereon. The clamp comprises an upper member 21 having a jaw plate 22 through which it is secured to the plate 8 by screws 29. The upper clamp member has a bifurcated end 23 carrying a pivot pin 24 on which the lower clamp jaw lever 30 is secured through the medium of its pivot ear 31.

The upper clamp member has a projection that is provided with a hemispherical socket

25 for the ball head 38 of the adjusting screw, the adjusting screw being held to the projection by means of an adjusting screw retaining plate 26 that engages the neck 37 of the 5 adjusting screw 35 and is itself secured to the projection by a screw 27 threaded to the tapped hole 28 in the projection of the clamp member 21.

10 The short end of the lower clamp jaw 30 is bifurcated as at 32 to receive the pivot block 33 into which the clamp adjusting screw 35 is threaded, the block 33 being pivotally secured to the bifurcations 32 by screws 34. The adjusting screw 35 is manipulated through the medium of a hand wheel 15 36.

15 The long end of the lower clamp jaw lever 30 is also bifurcated as at 39 to receive the shank 41 of the clamp table 40 which is adjustable by being pivoted at 42 to the lever.

20 It is to be noted that the bushings 15 have their portions of larger diameter to lie below the plate 8 and these portions are of the same thickness or depth as that of the clamp plate 25 22 so as to keep the stand held firmly against the top of the ironing table.

25 The lower edge of the inclined extension 10 lies flush with the plane which includes the lower faces of the bushings 15 and the plate 22. (See Figure 3.)

30 In the practical use of my invention, as will be seen from Figure 1 and Figure 2, the holder is clamped over the edge of the ironing board or table, the pad of the table preferably extending beneath the holder so that the act of clamping the holder in place also holds the pad and slightly presses the lower edge of the extension 10 into the pad.

35 Upon completing the ironing act the iron 40 is drawn across the pad to the extension 10, slid up the said extension and the lip 6 onto the top face of the receiving or top plate 4. Thus it will be seen that it is unnecessary to lift the iron in order to place it on the holder 45 or to lift it in order to remove it from the holder and apply it to the work on the table.

40 By providing the adjustable clamp of the construction shown and described a convenient and quick way is provided for mounting the holder on ironing boards or tables of 50 various thicknesses.

45 It is to be noted that the lip 6 does not touch the upstanding offset 9, but is spaced slightly from the same so that heat may not be conducted from the upper to the lower plates at this place, nor does the intermediate plate touch the offset 9. This construction leaves free air circulation between the several 55 plates and yet allows a practically continuous runway to be had from the ironing board surface to the rest surface of the upper plate 4.

60 In addition to the air surfaces between the plates the insulating bushings serve to prevent conduction of heat through the means by

which the several plates are secured together.

65 Note especially that with this invention as shown an electric iron may be left on the upper plate with the heat turned on for a 70 considerable period of time without scorching the cover of the ironing table.

75 From the foregoing description, taken in connection with the accompanying drawings, it is thought that the construction, operation and advantages of my invention will be readily apparent to those skilled in the art.

80 What I claim is:

85 1. In an iron holder, a top plate having a downwardly inclined lip along one edge, a bottom plate having an upstanding wall adjacent said lip and a downwardly inclined extension, means holding said plates spaced apart with said lip having its lower edge flush with the inclined extension, and a clamp secured to the lower plate and spacing it from an ironing table to which it may be attached, with the lower edge of the extension in contact with the ironing table.

90 2. In an iron holder, a top plate having a downwardly inclined lip along one edge, a bottom plate having an upstanding wall adjacent said lip and a downwardly inclined extension, means holding said plates spaced apart with said lip having its lower edge flush with the inclined extension, and a clamp secured to the lower plate and spacing it from an ironing table to which it may be attached, with the lower edge of the extension 95 in contact with the ironing table, said plate spacing and holding means comprising insulating bushings.

100 3. In an iron holder, a top plate having a downwardly inclined lip along one edge, a bottom plate having an upstanding wall adjacent said lip and a downwardly inclined extension, means holding said plates spaced apart with said lip having its lower edge flush with the inclined extension, and a clamp secured to the lower plate and spacing it from an ironing table to which it may be attached, with the lower edge of the extension 105 in contact with the ironing table, and an intermediate plate located in spaced relation between said top and bottom plates.

110 4. In an iron holder, a top plate having a downwardly inclined lip along one edge, a bottom plate having an upstanding wall adjacent said lip and a downwardly inclined extension, means holding said plates spaced apart with said lip having its lower edge flush with the inclined extension, and a clamp secured to the lower plate and spacing it from an ironing table to which it may be attached, 115 with the lower edge of the extension in contact with the ironing table, said plate spacing and holding means comprising insulating bushings, and an intermediate plate located in spaced relation between said top and bot- 120 125 130

tom plates, and insulating spacer washers located on said bushings between said plates.

5. In an iron stand, a bottom plate, a top plate having an upstanding flange along three faces and a lip along its fourth face, the bottom plate having an upwardly offset inclined extension adjacent said lip, constituting a functional continuation thereof, a clamp including a jaw plate fixed to and located beneath said bottom plate, and a pivoted jaw carried by said jaw plate in clamping cooperation therewith, and an adjusting screw connecting said pivoted jaw and said jaw plate, said jaw plate serving to hold said bottom plate spaced above a board to which a clamp is designed to be secured, the bottom face of said jaw plate and the lower edge of the said offset extension lying in approximately the same plane.
- 20 6. In an iron stand, a bottom plate, a top plate having an upstanding flange along three faces and a lip along its fourth face, the bottom plate having an upwardly offset inclined extension adjacent said lip, constituting a functional continuation thereof, a clamp including a jaw plate fixed to and located beneath said bottom plate, and a pivoted jaw carried by said jaw plate in clamping cooperation therewith, and an adjusting screw connecting said pivoted jaw and said jaw plate, the bottom face of said jaw plate and the lower edge of said offset extension lying in approximately the same plane.

7. In an iron stand, a bottom plate, a top plate having an upstanding flange along three faces and a lip along its fourth face, the bottom plate having an upwardly offset inclined extension adjacent said lip, constituting a functional continuation thereof, a clamp including a jaw plate fixed to and located beneath said bottom plate, and a pivoted jaw carried by said jaw plate in clamping cooperation therewith, and an adjusting screw connecting said pivoted jaw and said jaw plate, and an intermediate plate located between said top and bottom plates and insulated therefrom, said jaw plate serving to hold said bottom plate spaced above a board to which a clamp is designed to be secured, the bottom face of said jaw plate and the lower edge of the said offset extension lying in approximately the same plane.

8. In an iron stand for ironing tables, a plurality of horizontal metal plates spaced apart one above the other by insulating bushings and washers, the bottom plate having an upwardly offset extension inclined downwardly to afford a runway for the iron from the ironing table to the top metal plate, and a clamp securing the bottom plate on the top of the ironing table in spaced relation thereto.

9. In an iron stand for ironing tables, a plurality of horizontal metal plates spaced apart one above the other by insulating bushings and washers, the bottom plate having an

upwardly offset extension inclined downwardly to afford a runway for the iron from the ironing table to the top metal plate, and a clamp securing the bottom plate on the top of the ironing table in spaced relation thereto, said clamp comprising an upper jaw plate, a lower clamp jaw lever pivoted to said upper plate, an adjusting screw connecting said clamp plate with said clamp jaw lever, and an adjustable clamp table pivoted to said jaw lever and located beneath said upper jaw plate, said jaw plate serving to hold said bottom plate spaced above a board to which a clamp is designed to be secured, the bottom face of said jaw plate and the lower edge of the said offset extension lying in approximately the same plane.
